US00D762012S

(12) **United States Design Patent**
Alataas

(10) **Patent No.:** **US D762,012 S**
(45) **Date of Patent:** **** Jul. 19, 2016**

(54) **HELMET**

(71) Applicant: **Reem Jafar Alataas**, Stratford, CT (US)

(72) Inventor: **Reem Jafar Alataas**, Stratford, CT (US)

(**) Term: **15 Years**

(21) Appl. No.: **29/528,119**

(22) Filed: **May 26, 2015**

(51) LOC (10) Cl. **09-03**

(52) U.S. Cl.

USPC **D29/102**

(57) **CLAIM**

The ornamental design for a helmet, as shown and described.

DESCRIPTION

FIG. 1 is a perspective view of a helmet in accordance with the present design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the drawings depict environmental subject matter only and form no part of the claimed design.

1 Claim, 7 Drawing Sheets
